United States Patent Office

Des. 213,394
Patented Feb. 25, 1969

213,394

TISSUE DISPENSER

Robert Adell, Birmingham, Mich., assignor to Adell International Inc., Detroit, Mich., a corporation of Michigan

Filed Oct. 31, 1966, Ser. No. 4,471

Term of patent 14 years

U.S. Cl. D52—2
Int. Cl. D6—01

FIG. 1 is a side elevational view of a tissue dispenser showing my new design;

FIG. 2 is an end elevational view;

FIG. 3 is a top plan view;

FIG. 4 is a bottom view;

FIG. 5 is a side elevational view taken from the right of FIG. 2;

FIG. 6 is a perspective view of the tissue dispenser.

The undisclosed end of the tissue dispenser is a mirror image of the end shown.

I claim:

The ornamental design for a tissue dispenser, as shown and described.
